UNITED STATES PATENT OFFICE.

GEORGE W. SMITH, JR., OF CLEVELAND, OHIO, ASSIGNOR TO THE WHITE MOTOR COMPANY, OF CLEVELAND, OHIO, A CORPORATION OF OHIO.

INTERNAL-COMBUSTION ENGINE.

Application filed December 21, 1925. Serial No. 76,909.

My invention relates to internal combustion engines, and particularly to that type thereof wherein a combustible mixture ignited in the engine cylinder may comprise such heavy fuel as crude oil, kerosene or the like.

It has hitherto been proposed, in certain engines of this general type, to bring the combustible charge, comprising air and fuel, to such a high degree of compression that spontaneous ignition will occur from the heat of the compression; such engines, however, must be made exceedingly heavy, in order to withstand the stresses which are set up during their operation. In certain instances it has been proposed to burn a heavy fuel in engines without compressing the fuel mixture to a degree above the ignition point, but so far as I am aware, this has been attended by such undesirable results as incomplete combustion, carbonization of the fuel in the combustion chamber and difficulties in maintaining the timing of the firing under variable engine loads and speeds.

An object of my invention, therefore, is to introduce a heavy fuel such as a relatively heavy oil, into the combustion chamber of an engine, and to burn a mixture of such oil and air therein, without first bringing it to that high degree of pressure required for firing it as is necessary in engines of the high compression or so-called Diesel type.

Another object of my invention is to ignite the main working charge of heavy fuel and air in an engine, by first firing an auxiliary minor igniting charge which is preferably of a highly volatile nature and which is disposed in proximity to the main charge and fired at required predetermined intervals.

Another object of my invention is to accomplish the firing at the main charge by first maintaining the major and minor charges substantially separated until after the firing of the minor charge, and accomplishing consequent immediate ignition of the major charge by explosively mixing the burning minor charge therewith.

Another object of my invention is to accomplish the firing of the minor charge in the ordinary manner for igniting internal combustion engine charges by the use of a timed electrical ignition system.

Another object of my invention is to ac-

complish a most efficient introduction of the main charge comprising a relatively heavy fuel, into the engine combustion chamber.

Other objects of my invention and the invention itself will be readily apparent from the following description of an embodiment of my invention, and in which description reference will be had to the accompanying drawings, illustrating said embodiment for the purpose of explaining my invention.

Referring to the drawings:

Figure 1 shows a vertical transverse section taken through one of the cylinders of an internal combustion engine embodying my invention.

Figure 2 is a horizontal section taken upon a plane indicated by the lines 2-2 in Figure 1.

Figure 3 is a plan view of a fragmentary portion of the engine of the foregoing figures; and

Figures 4 and 5 are diagrammatic views illustrating certain aspects of my invention.

Referring now to the different figures in the drawings, in all of which like parts are designated by like reference characters, the engine comprises a cylinder 1, in which a piston 2, is reciprocated by means of a connecting rod 3, pivotally carried on a crank-shaft 4, journaled in bearings 5, in the crankcase 6. Above the cylinder 1, and communicating therewith there is a main combustion chamber 7 provided with an exhaust port 8, and an intake port 9. The intake port communicates with a passageway 10 extending to atmosphere and is adapted to be regularly opened and closed by the valve 11, suitably operated by a rocker arm 12, actuated from the crankshaft 4, through the gears 13 and 14, a camshaft 15, and a valve push rod 16. The ratio of the gearing between the crank and camshafts is two to one, as is common in four cycle engines, thus facilitating the operation of the valve 11, once in every second revolution of the crankshaft.

In juxtaposition with the main combustion chamber 7, there is a minor charge combustion chamber 17, which is preferably relatively small and spherical in form. Intermediate the chambers 7 and 17, and communicating with each there is a passageway 18, formed with relatively small terminating orifices 19 and 20, and with an intermediate enlarged central portion.

In a wall of the minor chamber 17, there is provided a spark plug 21, and adjacent thereto is an automatic valve 22, spring pressed by a spring 23, to its seat, wherein it closes the inlet passage 24, leading from a carburetor 25 to the chamber 17. The carburetor 25 is provided for the purpose of supplying a mixture of a relatively light and combustible hydrocarbon, such as gaso-
line and air, to the minor combustion chamber.

A second piston 26, of relatively small diameter, is disposed within a cylinder 27 and is adapted to be reciprocated at half the rate of reciprocation of the piston 2, in the cylinder 1. The piston 26, is formed with a longitudinal bore 28, and a transverse bore 29, which communicates with an annular groove 30, in the piston intermediate its ends. The groove 30 is adapted to be aligned with a passage 31 when the piston is in its uppermost or so-called compression position and when the piston is at its lowermost position the top wall thereof will be disposed above the level of the passage 31, thus preventing communication between the cylinder 27 and the combustion chamber 7. A high compression chamber 32, for the cylinder 27, is provided above the piston 26, and within this chamber an automatic valve 33 is provided for admitting a mixture of heavy fuel and air to the cylinder 27. The valve 33 is spring pressed by the spring 34 to its seat 35 and is adapted to be opened upon the suction stroke of the piston 26 and to be closed upon a compressive stroke thereof.

The passage 31 is preferably disposed in such angular relation to the combustion chamber 7 and so positioned with respect to the valve port 8 as to direct the inwardly rushing mixture of air and fuel against the exhaust valve 49, cooling the same and creating a turbulent flow of gases within the combustion chamber.

The mixture of heavy fuel and air is supplied through an inlet conduit 36 which is preferably provided with a venturi 37, at which venturi heavy fuel oil is supplied through a nozzle 38 from a reservoir 39. The air admitted may be heated in any suitable manner, as by an exhaust stove which, as illustrated, comprises a casing 40, enveloping the exhaust pipe 50, and a conduit 41 leading therefrom to the inlet conduit 36 at a point below the venturi 37. If desired the heated products of combustion, or air and the heated exhaust gases, may be substituted for air by providing a suitable communication with the exhaust pipe and admitting these gases to the inlet conduit 36. The volume of the mixture of air or gases and fuel is controlled by a valve 42, which in the present case is mounted in the inlet conduit 36, above the venturi, although other

and equivalent forms and arrangements of the fuel control may be used.

The piston 26 is reciprocated by means of a pitman 43, mounted on an eccentric 44, on the camshaft 45, which is driven by the crankshaft 4 through the gears 14 and 46. The eccentric 44 may be angularly adjusted on the shaft 45 by positioning the broached hubs 47 of the eccentric 44 on the splined portion of the shaft 45 and then clamping the hubs 47 to the shaft by tightening the bolts 48.

An exhaust valve 49 similar to the air inlet valve 11, is provided to control the flow of burned gases from the cylinder combustion chamber 7 to the exhaust pipe 50, the said exhaust valve being controlled in a manner like that of valve 11 by a rocker arm 51 together with a suitable valve push rod 52 and gear connections to communicate motion from the crankshaft 4.

The cams for operating the respective valve push rods 16 and 52, for the air inlet and exhaust valves are so disposed on the camshafts 15 and 45 that the inlet and exhaust valves will be alternately opened in the manner common in four cycle engines for fuel inlet and exhaust valves.

Assuming that by suitable fluid supply connections, a relatively volatile fluid such as gasoline is continually supplied to the carburetor 25, and a relatively less volatile fluid fuel is continuously supplied to the oil reservoir; the engine of the embodiment of my invention, herein illustrated and described operates as follows: The rotation of the crankshaft 4, will reciprocate the piston 2 which, on its downward movement, will reduce the pressure existing in the combustion chamber 7 to a fluid pressure lower than atmospheric pressure and the valves 11 and 22 will be caused to be drawn to their open position by the excess of the fluid pressure of atmosphere on their outer sides. With the continued movement of the piston 2 towards its lowermost position these valves will be held open and through the valve openings thereby created there will be drawn respectively, a mixture of gasoline and air through the valve opening controlled by the valve 22 and a relatively heavier flow of air through the valve opening controlled by the valve 11. The piston 26 meanwhile is moved downwardly and effects the opening of the automatic valve 33, causing a mixture of air and heavy fuel to be drawn through the valve opening controlled by the valve 33.

The venturi restriction 37 in the conduit 36, prevents the fluid in the conduit from maintaining itself at atmospheric pressure, and consequently the reduction of pressure in the conduit 36, intensified at the venturi 37, will result in the greater pressure of atmosphere which is exerted on the body of

liquid fuel in the reservoir 39, forcing such liquid fuel through the nozzle 38, in a semi-atomized condition, whence it will be conveyed by the inwardly rushing air through the conduit 36 and through the valve opening controlled by the valve 33 into the compression chamber 32.

The action of drawing the mixture of heavy oil and air into the chamber 32 will 10 continue only while the piston 25 is moving in a downward direction. By virtue of the adjustability of the eccentric 44 on the shaft 45, an angular disposition of the eccentric relative to that of the crank for 15 the piston rod 3, may be made so that the peripheral groove 30 will have been brought into alignment with the passage 31 just prior to the attainment by the piston 2 of its uppermost position wherein the compression 20 of the contents of the combustion chamber 7 is complete. This alignment effects expulsion of the mixture of heavy fuel oil and air, which has been highly compressed in the chamber 32 and the passage- 25 way 28 leading therefrom, into the combustion chamber 7, generally in an atomized condition.

The clearance space at the end of the stroke of the piston 26 being relatively small 30 compared to the space swept by the piston 26, the contents of the chamber 32 will be subjected to a high degree of compression, and when desired, this compression may be made so high as to approach the point of 35 spontaneous ignition of the heavy fuel oil and air mixture.

The alignment of the peripheral groove 30, with the passageway 31 opens a restricted 40 exit passage for the highly compressed and heated combustion mixture of heavy fuel oil and air into the combustion chamber 7 and insures the injection of fuel at a high velocity whereby the particles of heavy fuel oil will be injected into the much less highly 45 compressed air of the combustion chamber so as to penetrate the compressed air in the combustion chamber 7 and accomplish an intimate mixture of the heavy fuel oil particles with the air in which they are for the 50 moment, suspended.

Meanwhile the ignition chamber 17 and the intermediate chamber 18 are filled with a more highly volatile mixture comprising gasoline and air which is drawn through 55 the valve 22 on the downward suction stroke of the piston 2. The compression of the air in the combustion chamber will however, force back towards the ignition chamber 17, this body of volatile mixture without mixing 60 it to any great extent, with the compressed air in the chamber 7.

The pressure imposed upon the air in the combustion chamber 7, is communicated to the mixture of gasoline and air in the intermediate chamber 18, and the ignition 65

chamber 17, in such a way as to avoid turbulence therein, whereby intermingling of the contents of the chambers 18 and 17 on the one hand with the combustion chamber 7 on the other, is substantially prevented. 70

As the piston 2 approaches its uppermost position, and during the injection of the over-rich mixture of oil and air, the highly explosive mixture in the ignition chamber 17 is exploded by producing a spark in the well known manner at the point of the spark plug 21, projected within such chamber. The timing of the firing of the ignition charge 17 may be adjustably determined by adjustment of the timer 53, in the well known manner for timing the firing of four cycle engines, and the firing may be advanced to any suitable degree relative to the movement of the piston 2 toward its uppermost position, likewise the relative cycle movement of the piston 26 may be predetermined by adjusting the angular position of the eccentric 44 on the shaft 45 so that the piston 26 may relieve the compressed combustible mixture into the combustion chamber 7 at any desirable point before, at the time of, or after the piston 2 has reached the uppermost position, that is, the injection of the fuel may be advanced or retarded to any desirable degree depending upon conditions under which the engine is operated, the nature of the fuel employed, speed of propagation of flame ignition points to the combustion chamber and the speed at which the engine is to be operated. 90

It will be understood that the firing of the charge in the ignition chamber 17 will explosively eject the burning charge of gases from the chambers 17 and 18 into all parts of the combustion chamber 7, which at the time will contain a compressed charge of air with generally finely comminuted suspended particles of heavy fuel oil previously projected through the passage 31 into the combustion chamber 7. 105

The charge in the chamber 32 is preferably compressed five or six times the degree of compression of the charge in the combustion chamber 7 which may have its charge compressed to substantially the pressure commonly used in gasoline explosive engines; for instance the charge employed in the chamber 7 may be compressed to 75 pounds per square inch, while the charge in the combustion chamber 32 may be compressed to 120 450 pounds per square inch. 115

The relative volumes of the chamber 7 and the communicating chambers 17 and 18 are purposely such that there be maintained through the period of compression a substantial separation of the contents of the chamber 7 and the other two chambers, the line of contact between the contents of the respective communicating chambers 7 and 125 18 being, however, shifted toward the igni- 130

tion chamber 17 through the period of compression. The position of the piston 26 is preferably so adjusted, relative to the other parts, that the ignition of the charge, comprising finely atomized particles of fuel oil in the chamber 7, will occur before the particles of hydro-carbon fuel oil injected in to the chamber 7 will have had time to be chilled by precipitation on the walls of the cylinder and piston head which define the combustion chamber 7.

It has been found that through the cooperative effect of the piston 26 and the other parts, the preparation of the charge and the firing of the same can be so accomplished as to more completely effect the combustion of the charge than has been heretofore possible in engines of this general type and by the form and disposition of the ignition chamber and the intermediate fusiform chamber it has been found possible to prevent a contamination of the volatile igniting charge by the air and heavy fuel oil in the chamber 7, and that the mixture within the ignition chamber 17 particularly, is kept substantially uncontaminated and is retained in an explosive state.

The ignition of the contents of the combustion chamber 7 will heat the gases therein causing their rapid expansion which will force the piston downward on its working stroke; the continuing movement of the piston and consequent operation of the valves to the completion of the cycle will be readily understood from the foregoing description and analogous operation in ordinary four cycle engines, except that the use of heavier fuel will effect a slower expansion of the working charge and a longer continued more uniform working pressure will be exerted by the burning fuel than in those engines adapted to use gasoline or a like fuel.

Having thus described my invention, what I claim as new, and desire to secure by Letters Patent, is—

1. The method of introducing and firing a composite charge in the combustion chamber of an internal combustion engine, comprising the introduction and subsequent compression of a charge of atmospheric air, in then directing a stream of highly compressed over-rich mixture of hydrocarbon and air from one side of the compression chamber upwardly and inwardly toward the central portion of the head of the combustion chamber, in meanwhile providing a confined compressed minor charge of a more volatile mixture of hydrocarbon and air in communication with the compressed air being substantially unmixed therewith, and then igniting the said minor charge at a point remote from the chamber to introduce explosively the ignited volatile mixture to the mixture in the chamber.

2. The method of introducing and firing a composite charge in the combustion chamber of an internal combustion engine, comprising the introduction and subsequent compression of a charge of atmospheric air, in then directing a stream of highly compressed over-rich mixture of hydrocarbon and air from one side of the compression chamber upwardly and inwardly toward the central portion of the head of the combustion chamber against the exhaust valve, in meanwhile providing a confined compressed minor charge of a more volatile mixture of hydrocarbon and air in communication with the compressed air being substantially unmixed therewith, and then igniting the said minor charge at a point remote from the chamber to introduce explosively the ignited volatile mixture to the mixture in the chamber.

3. In an internal combustion engine, the combination with a cylinder of a piston therefor, a pair of oppositely disposed inlet ports in the head of the cylinder at the sides thereof, a valve for one of said ports, a carburetor, a relatively small ignition chamber, conduit means leading from the said carburetor to the other of said ports, a valve in the said conduit, a relatively enlarged portion of the said conduit comprising an ignition device in the said enlarged conduit portion, a portion of said conduit being disposed between its enlarged portion and its port and adapted to effect fluid communication between the said enlarged portion and the cylinder through said port, a second cylinder of relatively small volumetric capacity to that of the said first cylinder, a piston in said second cylinder adapted to compress a charge comprising a heavy hydrocarbon introduced into the said second cylinder and confined therein, means to operate said valve to release the highly compressed charge of hydrocarbon to the cylinder during the compression stroke of the piston for the first cylinder, said ignition device adapted to ignite a relatively more volatile mixture from the carburetor contained in the said ignition chamber to explode the same, the force of the explosion distributing the resulting burning charged portion through the said second part into the cylinder to ignite the charge of compressed air and hydrocarbon therein.

4. A motor comprising a cylinder, a piston reciprocal therein, means for supplying fuel to said cylinder, means for introducing an ignited fuel into said cylinder, the last named means comprising an ignition chamber and a fusiform conduit connecting said ignition chamber with said cylinder.

5. A motor comprising a cylinder, a piston reciprocal therein, means for supplying fuel to said cylinder, means for introducing an ignited fuel into said cylinder, the last named means comprising an ignition

chamber and a conduit having an enlarged portion with reduced orifices connecting said ignition chamber with said cylinder.

6. A motor comprising a cylinder, a piston reciprocal therein, means for supplying fuel to said cylinder, means for introducing an ignited fuel into said cylinder, the last named means comprising an ignition chamber and a conduit having an enlarged passageway with a reduced outlet orifice connecting said ignition chamber with said cylinder.

7. A hydrocarbon motor comprising a cylinder, a piston reciprocal therein, means for supplying a hydrocarbon fuel to said cylinder, means for introducing an ignited mixture of air and hydrocarbon into said cylinder, the last named means comprising

an ignition chamber and a fusiform conduit connecting said ignition chamber with said cylinder.

8. A hydrocarbon motor comprising a cylinder, a piston reciprocal therein, means for supplying a hydrocarbon fuel to said cylinder, means for introducing an ignited mixture of air and hydrocarbon into said cylinder, the last named means comprising an ignition chamber and a conduit having an enlarged central portion and reduced orifices connecting said ignition chamber with said cylinder.

In testimony whereof I hereunto affix my signature this 14th day of December, 1925.

GEORGE W. SMITH, JR.
